ANDRÉ LÉON VICTOR CLÉMENT DEBRIE, OF PARIS, FRANCE

METHOD FOR TREATING FILMS ARRANGED IN STRIPS

Application filed December 20, 1929, Serial No. 415,580, and in France January 31, 1929.

5 Cinematographic films and the like arranged in strips are generally developed, fixed and dried in continuously working machines wherein the different films secured together to form a continuous strip pass first through one or more vats containing the developer and then in succession through the washing vats, the fixing vats and lastly into the drying kiln.

10 Now the different films passing in succession through the machine may require to be immersed during varying times of reaction for a proper development and this causes some difficulty in the working of the machine.

15 My invention has for its object a method whereby each film or portion of film is allowed to pass through the developing bath during the exact time required without it being necessary to change the speed of the strip containing the film nor to slow down or to accelerate the movement of the films ahead of the film considered and still undergoing the developing process. It is neither necessary to use intermediary strips between 20 the successive films nor to go into intricate handling in the case of my invention.

25 According to my said invention the developer is distributed between a certain number of short vats each of which is immediately followed by a vat full of water, bromide-containing water or any suitable acidulated product adapted to wash the developed film and to prevent any further action of the developer.

30 Each film passes first in as many developer vats as may be required for its proper development. When this is accomplished it passes through the washing vats ahead of the last developer vat used. Obviously the total number of vats whether developer vats or washing vats, through which a film passes is the same for all the films. Thus each film is developed to the required extent and the machine works exactly as if the several films remained the same time in the developer.

35 Accompanying drawing gives a diagrammatic illustration of the invention, Figs. 1 and 2 showing the position of different films of the same strip in the developer and washing vats. The machine shown comprises vats

D followed each by a washing vat W of the same size, a film F (Fig. 1) which is properly developed after passing through a single developer vat will pass out of said vat into the adjacent corresponding washing vat and 55 thence into the following five washing vats. On the contrary a film F₁ (Fig. 2) which is properly developed only after passing through all six developer vats will only pass through the last water vat. All the films will 60 pass thus through seven vats which will be according to requirements, one developer vat and six water vats or two developer vats and five water vats and so on up to six developer vats and one water vat. 65

Each film passing out of a developer vat may be brought either into the adjacent water vat or into the next developer vat either by hand or through semi-automatic or entirely automatic devices. Any suitable inspecting 70 means allows the state of development of the film to be ascertained as it passes out of each developer bath.

The above arrangement though particularly intended for use in film development 75 processes may also be used with advantage for other operations where the different films require treatments of different duration, such as dyeing and even for operations on bands of any description. 80

What I claim is:

A method for treating a plurality of films arranged in a strip consisting in passing said strip continuously over a series of vats containing alternately a developer and a washing liquid, and extending loops of the strip, invariable length, into that number of developer vats corresponding to the desired development, and thereafter into such number of washing vats that the total number of extensions of the film into the two kinds of vats is a constant. 85

In testimony whereof I have signed my name to this specification. 90

ANDRÉ LÉON VICTOR CLÉMENT DEBRIE. 95
